(57) **CLAIM**

The ornamental design for an adjustable chaise lounger with hood in multiple positions, as shown and described.

DESCRIPTION

FIG. 1 is a perspective view of an adjustable chaise lounger with hood in lay flat position showing front, top, and left sides;

FIG. 2 is a top view thereof;

FIG. 3 is a front view thereof;

FIG. 4 is a right side view thereof;

FIG. 5 is a rear view thereof;

FIG. 6 is a left side view thereof;

FIG. 7 is a perspective view of an adjustable chaise lounger with hood in lay flat position with elevated chaise from the front, top, and left sides;

FIG. 8 is a top view thereof;

FIG. 9 is a front view thereof;

FIG. 10 is a right side view thereof;

FIG. 11 is a rear view thereof;

FIG. 12 is a left side view thereof;

FIG. 13 is a perspective view of an adjustable chaise lounger with hood in zero gravity position from the front, top, and left sides;

FIG. 14 is a top view thereof;

FIG. 15 is a front view thereof;

FIG. 16 is a right side view thereof;

FIG. 17 is a rear view thereof;

FIG. 18 is a left side view thereof;

FIG. 19 is a perspective view of an adjustable chaise lounger with hood in zero gravity position with elevated chaise from the front, top, and left sides;

FIG. 20 is a top view thereof;

FIG. 21 is a front view thereof;

FIG. 22 is a right side view thereof;

FIG. 23 is a rear view thereof;

FIG. 24 is a left side view thereof;

FIG. 25 is a perspective view of an adjustable chaise lounger with hood in seated position from the front, top, and left sides;

FIG. 26 is a top view thereof;

FIG. 27 is a front view thereof;

FIG. 28 is a right side view thereof;

FIG. 29 is a rear view thereof;

FIG. 30 is a left side view thereof;

(Continued)

FIG. 31 is a perspective view of an adjustable chaise lounger with hood in seated position with elevated chaise from the front, top, and left sides;

FIG. 32 is a top view thereof;

FIG. 33 is a front view thereof;

FIG. 34 is a right side view thereof;

FIG. 35 is a rear view thereof; and,

FIG. 36 is a left side view thereof.

The broken lines shown in the drawing are for the purpose of illustrating environmental structure and form no part of the claimed design.
